UNITED STATES PATENT OFFICE.

JOHN W. FREE, OF WOODLAWN, PENNSYLVANIA.

METHOD OF AND APPARATUS FOR POINTING RODS.

Application filed July 14, 1923. Serial No. 651,631.

To all whom it may concern:

Be it known that I, JOHN W. FREE, residing at Woodlawn, in the county of Beaver and State of Pennsylvania, a citizen of the United States, have invented or discovered certain new and useful Improvements in Methods of and Apparatus for Pointing Rods, of which improvements the following is a specification.

10 My invention relates to improvements in methods of and apparatus for pointing rods. It finds application in the pointing of rolled metallic rods, preparing them for introduction into the die-block in which the rolled rod is drawn to wire. The object of my invention is the rapid production of a point of superior quality.

The invention is illustrated in the accompanying drawings. Fig. I is a fragmentary view in front elevation, and Fig. II in vertical and transverse section of the pair of power-driven rolls which constitute the pointing machine. Fig. III is a view similar to Fig. II, Figs. II and III together illustrating successive stages in the point-forming operation. Figs. IV and V are views to larger scale showing the roll pass and material in course of shaping within the roll pass. Fig. IV is a view in vertical section on the plane coincident with the roll axes and accordingly transverse to the axis of the material; Fig. V is a view in vertical section on the plane coincident with the axis of the material. Figs. VI and VII are views corresponding to Figs. IV and V respectively and illustrating a further step in the performance of the method. Fig. VIII is a view in elevation of the finished article, the pointed end of a rod, ready for insertion in a draw-block.

Referring first to Figs. I and II, the pointing machine in which and in the operation of which my invention is achieved consists essentially of a pair of power-driven rolls 1 and 2, rotating constantly in the directions indicated by the arrows, Fig. II. The faces of these rolls are formed with a plurality of circumferential recesses. These recesses are of graded size, diminishing from right to left, as seen in Fig. I.

Each circumferential recess is made up of two parts: a part 3 of larger dimensions, and a part 4 of smaller dimensions, and at the points where these parts join there is a

region 5 of tapering cross-section. The 55 rolls are so set and the succession of recesses so arranged that the corresponding portions of the recesses come to register as the rolls rotate. The larger portions 3 of the recesses cooperate to form an opening of such size that the material may be introduced through the opening in right-to-left direction (Fig. II), while the rolls continue to rotate, so that the material comes to position, as indicated at R, Fig. II, ready to be 60 65 acted upon.

It is the smaller portions of the circumferential recesses the portions 4, which cooperate to form the effective and material-reducing roll-pass. It will be perceived, on 70 examining Fig. II with care, that the material R introduced between the rolls and brought to the position shown, will presently, as the rolls continue to rotate, be powerfully grasped between the opposite faces 75 of the narrowed pass. The material will be so grasped at a point remote from its tip, at the point r. And it will be perceived that as the rolls, having so gripped the material R, continue in rotation, they will roll 80 the rod down, beginning at the point r and continuing to the free left-hand end of the rod, and that as they roll, they will gradually eject the rod from the roll pass in a left-to-right direction. Fig. III illustrates, 85 when brought into comparison with Fig. II, the operation just described.

In operation an attendant thrusts in the material, R, while the large portions of the recesses are in register, to the position indicated in Fig. II. Rolling follows and the rod is ejected, its end having been reduced somewhat. The attendant then, when the larger portions of the recesses are again in register, re-introduces the tip of the rod, into 90 the same pass, but before re-introduction he turns the rod on its axis through a quarter turn, or substantially so. The rolls then repeat their operation.

Having begun the pointing operation in 100 a larger pass, say the pass on the extreme right, Fig. I, and having so effected rolling twice repeated, or more, the attendant proceeds similarly to introduce the rod and to cause it to be rolled in the succeeding passes 105 to the left. But into each succeeding pass he introduces the material to a point short of that where the rolls in the preceding pass

engaged the material. Referring to Fig. VIII, in the first pass the rolls engaged the material at *r*, in the second at *s*, in the third at *t*, and so on.

5 All that I have up to this point described is already known to the art.

A difficulty with this machine as it hitherto has been constructed, and with the operation as it hitherto has been conducted, 10 is that in rolling the tip of the rod fins of metal are spread between the rolls on either side of the grooves 4, and these fins extend from opposite sides of the partially rolled point. As in the progress of rolling the 15 article is turned and rolled again, these fins are folded upon and crushed into the surface of the article. The result is a point which is of a splintering structure, weak, easily broken, and breaking in a ragged break, and 20 on such account unsatisfactory and productive of difficulty when it comes to insertion into a draw-block and to subject 25 tion to wire-drawing instrumentalities and wire-drawing strains. My invention consists in a modification in roll configuration and a corresponding modification in the pointing operation, in consequence of which the point which is formed, instead of being of splintered structure, is massive and coherent throughout. It will not splinter and 30 break, and serves well in the wire-drawing apparatus.

My invention will best be understood by considering Figs. IV-VII. I form the recesses 4 in the roll faces, not as simple semi-circular recesses, as hitherto they have been. I form them as recesses which are in the main, and essentially, semi-circular. But I 35 bevel the corner where the surface of the recess meets the general surface of the roll. This is indicated at 6. I do not limit myself to particular proportions, but it will be observed in Fig. IV, that this bevel cuts away on either side about 30° of the semi-circular 40 curvature of groove 4, and is inclined at an angle of 30° or more to the cylindrical face of the roll body. Such proportioning is adequate to accomplish my ends.

The rolls being so particularly shaped, the 45 rolling operation will readily be understood. In these Figures IV-VII the lines *a* indicate the original contour of the rod. The first rolling effects modification in cross-sectional shape, from the dotted circle *a*, Fig. IV, to the smaller circle with lateral bulges or protrusions which appears in full lines and cross-hatched. Instead of the fins developed along either side of the article between the rolls as hitherto shaped, the article under 50 treatment between the rolls modified in shape according to my invention has low broad rounded protrusions *b*.

Proceeding now to consideration of Figs. VI and VII, the same roll pass is shown, 55 also the same groove. But in Figs. IV and V

the first operation upon the material is illustrated, and in Figs. VI and VII the second. After the rolls have acted once on the material, in the manner illustrated in Figs. IV and V and now described, the material 70 is turned through a quarter turn and introduced again into the same roll-pass, and there undergoes the particular shaping illustrated in Figs. VI and VII. Consideration of Figs. VI and VII will show that the roll surfaces at the very middle of the pass are engaging the surface of the material from the point *c* to the point *d*, while the crushing strain exerted upon the protuberance *b* beginning at the point *e* continues to the 80 very middle of the pass at point *f*. The body of the rod is thus securely held; the crushing strains come vertically upon the protuberance *b*. It is not folded over, but 85 is crushed down into the body of the material. The surplus metal is taken care of, not in developing a new protrusion, but in extension in length. Thus, instead of the defective splintered structure of the point 90 as rolled hitherto in machines of this sort, I produce a point which is solid and coherent and integral throughout.

In other respects the pointing operation is that well known and indicated above.

In Fig. VIII I have purposely exaggerated the stepped configuration of the point. I have done this to bring out more clearly the characteristics of the invention. It will be understood that the point as actually developed tapers more gradually than my diagrammatic figure would indicate.

I claim as my invention:

1. In a rod-pointing machine a pair of rolls mounted for cooperation, each provided with a series of recesses of graduated size, the recesses of the two series cooperating to form a succession of roll passes, the grooves which form the successive roll-passes being in individual cross-section semi-circular, with beveled edges.

2. In a rod-pointing machine including in its structure a pair of continuously rotating grooved rolls, the grooves extending circumferentially and in continuity around the roll bodies and being throughout part of their extent widened to allow free passage of the material and in part narrowed to engage and reduce the material, the grooves throughout the narrowed portion of their extent being bevel-edged.

3. The method herein described of pointing a rod which consists in rolling its tip repeatedly and with quadrant turns between successive rollings from points adjacent the tip to the tip between grooved rolls whose grooves are semi-circular with beveled edges.

4. The method herein described of pointing the end of a rod which consists in causing the rod to be engaged between rolls at a point remote from its tip and rolled and

elongated from the point of initial engagement to the tip and brought to a shape circular in cross section with opposite rounded protrusions, and then causing it to be engaged a second time between rolls at a point remote from the tip and rolled and elongated from such point of engagement to the tip, and in such second rolling sinking said

protrusions into the body of the material, without folding. 10

In testimony whereof I have hereunto set my hand.
